COMBINED INVALID SERVING TRAY AND SUPPORT THEREFOR

Stanford Shepley Stevens, 42 Scott St., Pawtucket, R.I.

Filed Mar. 23, 1962, Ser. No. 69,389

Term of patent 14 years

(Cl. D44—10)

FIGURE 1 is an exploded perspective view of a combined invalid serving tray and support base therefor, showing my new design.

I claim:

The ornamental design for a combined invalid serving tray and support therefor, as shown.
